Letters Patent No 395, dated July 8th 1851

u u

The Schedule referred to in these Letters Patent and making part of the same

To whom it may concern.

Be it known that I, John S. Rathbone, of the city of Albany, in the State of New York, have produced a new and original design for

10

Des. 395

ornamenting the plates of a parlor Franklin Stove; and I hereby declare that the annexed drawings are a full and accurate delineation of the plates which form the Franklin Stove; the side plates not represented being symmetrically similar to the one shown, and the half of the hearth, plates, Back Plate and front plates and the front door plates not represented being also symmetrically similar to the plates and parts of plates shown.

What I claim as my production and desire to secure by Letters Patent is the combination of and arrangement of ornamental figures and forms represented in the accompanying drawings forming together the ornamental designs for the plates of a Franklin Stove.
